Attorney.

UNITED STATES PATENT OFFICE

HUGO SCHMEISSER, OF SUHL, GERMANY

AIR PISTOL

Application filed February 13, 1928, Serial No. 254,135, and in Germany January 25, 1927.

In the constructional types of air pistols so far known the cocking of the air piston is effected either by means of a special key supplied with the weapon, or else by means 5 of the barrel which in this case serves as the cocking lever. Both constructional forms have practical drawbacks as, in the first, the key is liable to be lost while in the second the barrel is apt to be bent through repeated use. 10 These defects are avoided according to the present invention by reason of the fact that the setting of the piston is effected by tilting an air cylinder upwards which projects rearwardly of the butt of the weapon and the piston 15 ton of which cooperates with a setting lever located in the back of the butt.

Such a construction not only obviates the defects mentioned above, but possesses the advantage that it is possible to provide as 20 large an air chamber as possible without substantially exceeding the longitudinal dimensions determined by the barrel and butt of the pistol. In addition to this a very favourable centre of gravity position is obtained for 25 the weapon when held in the hand, which is a very important consideration in air pistols used for sport purposes. By means of the air cylinder, which is adapted to be tilted upwards, and in which the barrel is located, a 30 large lever arm is created by means of which the pistol can be cocked or set without trouble and without it being necessary to have recourse to a special implement or tool.

The accompanying drawings show a constructional form of the invention.

Figure 1 is a lateral elevation of the air pistol in the closed position.

Figure 2 shows the pistol also in lateral elevation but partial longitudinal section, 40 with the air cylinder and the barrel, in the $\frac{3}{4}$ upwardly tilted position.

Figure 3 is a side view partly in section of the barrel and a portion of the cylinder, and

Figure 4 is an elevation of the air piston. 45 As can be readily seen from the drawings the air cylinder *b* is pivotally mounted upon the butt *a* of the pistol and carries the barrel *c* at its forward end. The attachment of the air cylinder is effected in such a way that it 50 projects beyond the rear part of the butt, but

at the same time it does not materially exceed the vertical plane of the rear lower end of the butt.

In the air cylinder *b* there is mounted in the manner already known the air piston *d* 55 with its pressure spring *e* bearing against the end cap *f*.

For the purpose of cocking or setting the weapon, in the piston part of the butt *a* the cocking lever *h* is pivotally mounted on the 60 pin *g*, the free end of which lever engages with the stop *i* of the air piston.

If the barrel *c* together with the air cylinder *b* be swung upwardly on the pivot pin *j* 65 away from the butt *a*, the lever *h* will push the air piston *d* towards the rear of the air cylinder *b* to such an extent that the sear *k* will spring into the recess *m* in the piston. After this the air cylinder with the barrel is 70 swung back to its closed or firing position against the butt.

As may be seen from Figure 3 the barrel is so mounted upon the air cylinder as to be tiltable and fixable, in such a way that an easy and commodious introduction of the 75 shot into the barrel is rendered possible.

The trigger *o* when pulled presses against the lever arm *p* of the sear *k*, whereby the piston is freed from tension and the shot is ejected from the barrel. The projection *s* 80 provided on the lever arm *p* serves as a pressure surface for the trigger.

Having now particularly described and ascertained the nature of my said invention and in what manner the same is to be performed, I declare that what I claim is:—

1. An air pistol comprising a butt; an air cylinder pivotally mounted on said butt at approximately intermediate the ends of the cylinder so that it projects rearwardly of the rear part of the butt; and a spring-actuated piston in said cylinder which is placed in cocked position in the cylinder by forcing the rear end of the cylinder toward the butt around the pivotal mounting.

2. An air pistol comprising a butt; an air cylinder pivotally mounted on said butt at approximately intermediate the ends of the cylinder so that it projects rearwardly of the rear part of the butt; a cocking lever piv- 95 100

otally mounted on said butt; and a spring-actuated piston in said cylinder which is placed in cocked position in the cylinder by forcing the rear end of the cylinder toward the butt around the pivotal mounting whereby the lever forces the piston backwardly in the cylinder.

3. An air pistol comprising a butt; an air cylinder pivotally mounted on said butt at approximately intermediate the ends of the cylinder so that it projects rearwardly of the rear part of the butt; a cocking lever pivotally mounted on said butt; a spring-actuated piston in said cylinder which is placed in cocked position in the cylinder by forcing the rear end of the cylinder toward the butt around the pivotal mounting whereby the lever forces the piston backwardly in the cylinder; and a sear pivotally mounted to the cylinder for holding the piston in the cocked position.

In testimony whereof I affix my signature.
HUGO SCHMEISSER.
